[57] CLAIM

The ornamental design for a door mirror, as shown and described.

DESCRIPTION

FIG. 1 is a front, right side perspective view of a door mirror showing our new design;

FIG. 2 is a front elevational view thereof, the door shown in broken lines for illustrative purposes only;

FIG. 3 is a side elevational view thereof, the opposite side being a mirror image and the door shown in broken lines for illustrative purposes only;

FIG. 4 is a rear elevational view thereof;

FIG. 5 is a top plan view thereof; and

FIG. 6 is a bottom plan view thereof.

FIG. 1

FIG. 2
